BICYCLE SEAT, OR SIMILAR ARTICLE

Charles V. Wrobel, Lake Forest, Walter Dian, Downers Grove, and Gerald Golden, Highland Park, Ill., assignors to Excel Incorporated, Franklin Park, Ill.

Filed Sept. 18, 1969, Ser. No. 19,199

Term of patent 14 years

Int. Cl. D12—14

U.S. Cl. D90—16

Fig. 1

Fig. 2

Fig. 3

Fig. 4

Fig. 5

FIG. 1 is a side elevational view of a bicycle seat or a similar article embodying our new design.

FIG. 2 is a side elevational view of the bicycle seat shown in FIG. 1 looking at the opposite side of the seat from that shown in FIG. 1.

FIG. 3 is a top plan view of the bicycle seat shown in FIGS. 1 and 2.

FIG. 4 is an end view of the bicycle seat looking toward the rear end of the seat; and

FIG. 5 is a front end view of the bicycle seat.

We claim:

The ornamental design for a bicycle seat, or similar article, as shown.
